(57) **CLAIM**

I claim the ornamental design for a V-shaped pull, as shown and described.

DESCRIPTION

FIG. 1 is a perspective view of a V-shaped pull design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a perspective view shown in environmental use; and,
FIG. 9 is an alternate perspective view shown in environmental use.

The broken lines shown represent unclaimed subject matter and form no part of the claim design.
